[57] CLAIM

The ornamental design for a combined toy animal figure, book and holder therefor, as shown.

DESCRIPTION

FIG. 1 is a front elevation view of a combined toy animal figure, book and holder therefor, showing my new design;

FIG. 2 is a bottom end elevation view thereof;

FIG. 3 is a top end elevation view thereof;

FIG. 4 is a right side elevation view thereof, the left side elevation view being a mirror image thereof;

FIG. 5 is a front elevation view thereof in open position; and,

FIG. 6 is an elevation view of the opposite side of FIG. 5.

FIG. 1

FIG. 2

FIG. 3

FIG. 4

FIG. 5

FIG. 6
